UNITED STATES PATENT OFFICE.

GEORGE ELLIS NECKLES, OF ZANESVILLE, OHIO, ASSIGNOR OF ONE-HALF TO GUST N. CALIS, OF ZANESVILLE, OHIO.

POWDER DISPENSER.

Application filed August 29, 1924, Serial No. 735,028. Renewed May 20, 1927.

The present invention relates to improvements in powder dispensers and has for an object to provide a device for use in pool and billiard rooms for spraying powder upon the hands of the players.

Another object of the invention resides in providing a device of this character for attachment to the wall or other convenient place and which may be easily operated to dispense the powder in a number of sprays without waste of the powder or spilling the same.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a front elevation of an improved powder dispenser constructed according to the present invention.

Figure 2 is a side view of the same.

Figure 3 is a cross section taken on the line 3—3 in Figure 1.

Figure 4 is a longitudinal section taken through the device.

Figure 5 is a similar view taken on the line 5—5 in Figure 4, and

Figure 6 is a transverse section taken on the line 6—6 also in Figure 4.

Referring more particularly to the drawings 7 designates a container made of wood or other appropriate material and shown as rectangular in cross section in Figure 3, although any appropriate shape may be given the receptacle.

This receptacle is adapted to hold a quantity of powder which is poured therein through the top cover 8 secured as by the pivoted latches 9 to one side wall of the receptacle. To one side of the receptacle is a block 10 to which is affixed an attaching plate 11 projecting beyond opposite sides of the device and having the perforations 12 to receive screws or other fastening means by which the device is attached to a wall or other support.

The bottom 13 of the powder receptacle is provided with perforations 14, being shown as six in number although a greater or lesser number may be used and valve pins 15 are mounted for vertical reciprocating movement in the receptacle and in po-

sition to enter the openings 14, the pins having closure collars 16 adapted to rest upon the bottom 13 about the perforations.

The upper ends of the valve pins 15 carry spaced flanges 17 and 18 for engaging opposite sides of the cross head 19. This cross head is normally drawn down by the coil springs 20 attached at the sides of the cross head, as shown in Figure 5 and to the bottom 13. The springs will normally hold the valves closed so as to prevent the issuance of the powder.

An operating arm 21 provided with a bifurcate inner end to straddle the central valve pins is secured at 22 in the receptacle 70 and projects through a slot 23 in one side wall of the receptacle. An operating hand piece 24 is connected to the projecting end of the arm, so that by lifting upon the hand piece 24 the cross head 19 is raised. The 75 arm 21 is so arranged as to strike the upper wall of the slot 23 before the lower ends of the valve pins 15 rise completely out of the perforations 14 in the bottom 13. The lower ends of the valve pins which project beyond the collars 16 thus form guides for the pins and in addition they are shown to loosely fit in the perforations 14 leaving annular spaces thereabout for the discharge of the powdered material in a thin annular film. Both the collars 16 and the lower projecting ends of the valve pins will serve as plungers to force the powder outwardly through the perforations 14 when the operating mechanism is released after being lifted. The wall of the powder receptacle is spaced substantially away from the side edges of the collars 16, so as to avoid any interference by the collars with the free movement of the powder to the openings 14. Moreover the valve pins 15 are elongated in order that the cross head 19 and operating mechanisms may be placed in the upper portion of the powder receptacle thus not interfering with the movement of the powder downwardly and out through the openings 14 whenever the valve pins are lifted.

A powder delivery box 25 is carried beneath the powder receptacle and is enclosed at two sides, its bottom and rear with one end, indicated at 26 left open to permit the insertion of the hand of the players to receive the powder.

One side wall of the receptacle is provided with an upper part 27 hinged at 28

to the lower part and this upper hinged part carries eyes 29 to receive the latches 9 by which the cover is fastened in place. The cover 8 is provided with side flanges 30 and an end flange 31 to extend about the upper portion of the receptacle but the flanges 30 terminate short of the cover at the wall portion 27.

In the use of the device the springs 20 normally hold the valves seated as shown in Figures 1 and 2 and any loss of powder is avoided. To dispense the powder, insert the fingers of the left hand into the opening 26 in the box 25 and beneath the powder apertures. At the same time push with the thumb of the left hand the hand piece 24 which will lift the cross head and the valves permitting of the discharge of the powder. The projecting ends of the pins extending through the openings 14 in the bottom 13 will guide the movement of the valves and the cross head and the collars 16 will not only close the openings, but will restrict the movement derived from the action of the springs 20.

The cover 8 may be easily removed when the device is to be replenished with powder and by swinging the upper hinged wall section 27 downwardly as shown in dotted lines in Figure 4 access may be had to the cross head and interior parts.

It is obvious that various changes and modifications may be made in the details of construction and design of the above specifically described embodiment of this invention without departing from the spirit thereof, such changes and modifications being restricted only by the scope of the following claims.

What is claimed is:—

1. A powder dispenser comprising a receptacle for the powder having a perforated bottom, valve pins in the receptacle disposed loosely in the perforations of the bottom, collars on said valve pins adapted to close the perforations when the pins are lowered, said collars being substantially spaced from the walls of the powder receptacle to allow free flow of the powder to the perforations in the bottom, and means to raise and lower the pins with the collars thereon.

2. A dispenser for powdered material comprising a receptacle for holding a quantity of the powdered material, said receptacle having a bottom with perforations therethrough, valve pins movably mounted in said receptacle and projecting into said perforations, means to reciprocate the valve pins, valve collars on said valve pins adapted to rest against the bottom for closing the perforations when the valve pins are in one position, said collars being substantially spaced from the walls of the powder chamber to allow free flow of the powder to the perforations in the bottom, and a protective casing beneath said perforated bottom for the insertion of the hand and to prevent waste of the powder.

3. A dispenser for powder comprising a receptacle for the powdered material having a perforated bottom, valve pins disposed in said receptacle and having their lower ends disposed loosely in the perforations of the bottom, valve collars on said pins normally closing against said bottom about the perforations and substantially spaced from the walls of the powder chamber to allow free flow of the powder to the perforations in the bottom, and means in the upper portion of the powder receptacle remote from the perforated bottom and said collars for lifting the valve pins and collars.

4. A powder dispenser comprising a receptacle having a removable cover and a perforated bottom, means whereby said receptacle may be attached to a support, a dispensing box disposed beneath the receptacle and closed at its sides, bottom and one end, the other end being open, a series of valve pins mounted for reciprocating movement in said receptacle and guided in the perforations of the bottom, said pins having collars to close against the bottom, a cross head connected to the upper ends of said pins, an arm fulcrumed in the receptacle and disposed beneath said cross head, said arm projecting to the exterior of the receptacle, an operating piece connected to said arm and means for arresting the lifting movement of said arm before said pins are entirely removed from said perforations.

GEORGE ELLIS NECKLES.
